(57) **CLAIM**

The ornamental design for a open end wrench, as shown and described.

DESCRIPTION

FIG. 1 is a perspective view of an open end wrench showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof with a first variant of the broken lines;

FIG. 9 is a perspective view thereof with a second variant of the broken lines;

FIG. 10 is a perspective view thereof with a third variant of the broken lines;

FIG. 11 is a perspective view thereof with a fourth variant of the broken lines;

FIG. 12 is a perspective view thereof with a fifth variant of the broken lines;

FIG. 13 is a perspective view thereof with a sixth variant of the broken lines;

FIG. 14 is a perspective view thereof with a seventh variant of the broken lines;

FIG. 15 is a perspective view thereof with an eighth variant of the broken lines; and,

FIG. 16 is a perspective view thereof with a ninth variant of the broken lines.

The broken lines shown in the drawings represent unclaimed environmental subject matter.
